CLAIM

The ornamental design for a “capsule for a flavoring substance,” as shown and described.

DESCRIPTION

FIG. 1 is a front view of a capsule for a flavoring substance showing our new design, wherein the rear view is a mirror image thereof;

FIG. 2 is a right side view as taken from FIG. 1, wherein the left side view is a mirror image of the right side view;

FIG. 3 is a top view of the capsule including a protective foil; and,

FIG. 4 is bottom view of the capsule, wherein the dot-dash-dot line forms a boundary of the claimed design and the dashed lines therewithin form no part of the claimed design.
